(57) **CLAIM**

The ornamental design for a main body of image inspection camera, as shown and described.

DESCRIPTION

FIG. 1 is a front, top, and right side perspective view of a main body of image inspection camera showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines in the figures show portions of the main body of image inspection camera that form no part of the claimed design.
